(57) **CLAIM**

The ornamental design for a clamp for matching drumsticks, as shown and described.

DESCRIPTION

FIG. 1 is a top front perspective view of a clamp for matching drumsticks showing our new design;

FIG. 2 is a top view thereof; and,

FIG. 3 is a front perspective view thereof.

In FIG. 3, the broken lines illustrating drumsticks show the design in use and form no part of the claimed design.

1 Claim, 2 Drawing Sheets

FIG. 1

FIG. 2

FIG. 3
